PULL TAB

Nick S. Khouri, Chicago, Ill., assignor to Continental Can Company, Inc., New York, N.Y., a corporation of New York

Filed Mar. 11, 1966, Ser. No. 1,413

Term of patent 14 years

(Cl. D58—26)

FIG.1

I claim:

The ornamental design for a pull tab as shown.
